UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,138,763.

Specification of Letters Patent.

Patented May 11, 1915.

Application filed August 3, 1912. Serial No. 713,048.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

My invention relates to electric switches.

It has among its objects to provide an improved electric snap switch of the revoluble type wherein a rotary contact carrying member is adapted to make or break the circuit connections of a plurality of circuits or branches of a single circuit with a quick snap action.

A further object of my invention is to provide improved means for supporting and housing said switch mechanism.

Other objects and advantages of my invention will hereinafter appear.

In order to clearly and fully disclose my invention, I have illustrated one embodiment of the same in the accompanying drawings. It is to be understood, however, that the form herein illustrated is susceptible of modification.

Figure 1 shows a side elevation of the assembled device when connected in circuit. Fig. 2 is a central longitudinal sectional view of the switch and switch casing. Fig. 3 is a sectional view on line 3—3 of Fig. 2. Fig.

4 is a longitudinal sectional view of the rotary commutating member. Fig. 5 is a plan view on line 5—5 of Fig. 2. Fig. 6 is a perspective view on line 6—6 of Fig. 2. Fig. 7 is a diagram of the circuit connection of the switch.

The switch herein illustrated is of the feed through type wherein two similarly shaped insulating bases 1 and 2 are inclosed within a feed through receptacle and connected by a central sleeve 3, a revoluble circuit controlling member 4 being mounted upon said sleeve between said bases and being provided with contacts 5 arranged to engage the contacts 6 carried by said bases.

The bases 1 and 2 are substantially disk-shaped and provided with annular recesses 7 in their adjacent faces, which recesses surround the central bore through which the sleeve 3 is passed. The bottoms of these recesses are provided with inclined or ratchet

faces, as shown in Fig. 6, four ratchet faces 8 being shown. As illustrated, two of these inclined faces carry contacts 6 which are flat and fit over the inclined faces. It is to be noted that when the contacts 6 are in a position upon the ratchet faces, all four of the latter are of substantially the same conformation and size. These contact members 6 are held in position by means of screws 9 which extend through in opposite directions to the outer faces of the bases and are there attached to terminal plates 10 carrying binding screws 11. As shown in Figs. 2 and 5, the ends 12 of the sleeve 3 are overturned on the outer faces of the bases adjacent the binding screws and are secured to the bases by sinking the overturned portions into the insulating material.

The revoluble operating member 4 is carried upon the sleeve 3 between the bases 1 and 2 and is substantially disk shaped, having a slightly larger radius than the bases 1 and 2. The member 4 is provided with annular recesses 13 in its upper and lower faces registering with the recesses 7 in the adjacent faces of the bases 1 and 2 and cooperating therewith to form a plurality of annular chambers surrounding the sleeve 3. In the annular recesses 13 are housed the contacts 5 which are resilient and bent into substantially U-shape and connected together at their inner ends by suitable screws or rivets 14. As shown in Fig. 4, the recesses 13 form an inner wall 15 which serves to insulate these contacts from the sleeve 3. When this revoluble member 4 is in position upon the sleeve 3, as shown in Fig. 2, and is rotated, the contacts 5 carried thereby engage the stationary contacts 6 in a predetermined order. Due to the conformation of the stationary contacts and the resiliency of the movable contacts, the latter successively make and break contact with the former with a quick snap action.

In Fig. 7 I have diagrammatically illustrated the circuit connections for the device when adapted to control a plurality of heating coils 16 and 17. It is to be understood that two conductors are attached to the upper binding posts 11, while one conductor passes through the sleeve 3 and is tapped in between the two heating coils 16 and 17, the opposite ends of which are brought up to the bottom binding posts 11. When the member 4 is rotated so that one

of its sets of contacts engages with the diagonally opposite upper and lower contacts shown in Fig. 7, the circuit is either established through the coil 16 or the coil 17. If desired, these coils may be given different values so that different heats may be obtained. It is to be noted that when both sides of the movable contacts are in engagement with both sets of the stationary contacts, the two coils are connected in parallel. Obviously, the desired connections of the coils may be obtained by successively rotating the member 4 to the desired position.

15 The switch mechanism is inclosed in an improved receptacle of the feed through type. Cylindrical casings 18 are attached to each end of the bases 1 and 2 by beading or spinning them upon the same as at 19.

20 Removable caps 20 are preferably carried upon the ends of these casings, catches 21 being provided upon the casings which are adapted to snap over annular shoulders 22 upon the caps. In order that these caps 25 may be released by compressing the casings in a well known manner, recesses 23 are provided in the periphery of the bases beneath the same. The caps 20 are preferably provided with insulating linings 24 and insulating sleeves 25 in the conductor openings which have annular flanges 26 arranged to hold the linings in position.

It is to be noted that in my improved construction the parts are securely held together by means of the sleeve and that when the revolute member is rotated the circuit is broken with a quick snap action. Further, the terminals of the device are readily accessible, it only being necessary to remove the caps when it is desired to change the connections. The whole device is so inclosed as to fully protect the contacts and to present a neat and pleasing appearance. The revolute contact member is conveniently located so that it may be readily adjusted. By suitably indicating the several positions of the same upon one of the parts of the receptacle as shown in Fig. 1, this contact member also serves as a visual indicator of the condition of the switch. The whole device may be very readily and cheaply manufactured and is of a rugged construction.

While I have described one form of my invention in order to clearly and fully dis-

close the same, I do not restrict myself to the exact construction shown for the purpose of illustration.

What I claim as new and desire to secure by Letters Patent of the United States is:

60 1. A feed through electric switch comprising, in combination, a pair of spaced insulating bases, a rotatable insulating member therebetween, the adjacent faces of said bases and said member having complementary annular recesses, a plurality of contacts on said bases and said member within said recesses, and a tubular sleeve extending through said bases and said member and holding the former against separation and relative rotation and affording a conductor passage therethrough.

70 2. A feed through electric switch comprising, in combination, a pair of spaced insulating bases, a rotatable insulating member therebetween, the adjacent faces of said bases and said member having complementary annular recesses, 75 a plurality of stationary contacts in said base recesses arranged in the form of ratchets, a plurality of resilient contacts in the recesses of said member adapted to make and break circuit between said stationary contacts in a predetermined sequence upon rotation of said member and a tubular metallic sleeve insulated from all of said contacts for holding said bases against relative separation and rotation and constituting a passage for a conductor therethrough and through said member.

80 3. In an electric switch, in combination, a plurality of insulating bases, a rotatable member therebetween, the adjacent faces of said bases and said member having complementary annular recesses, a plurality of contacts on said bases and said member within said recesses, tubular means forming the axis of said member and holding said bases against separation and relative rotation, a resilient casing rigidly secured to 85 each of said bases, and a removable cap for each of said casings adapted to be snapped over the ends of the latter.

90 4. In an electric switch, in combination, a plurality of insulating bases, a rotatable member therebetween, the adjacent faces of said bases and said member having complementary annular recesses, a plurality of contacts on said bases and said member within said recesses, tubular means forming the axis of said member and holding said bases against separation and relative rotation, a resilient casing rigidly secured to 95 each of said bases, and a removable cap for each of said casings adapted to be snapped over the ends of the latter.

100 In witness whereof, I have hereunto subscribed my name in the presence of two witnesses.

CHARLES J. KLEIN.
